Application June 15, 1940, Serial No. 340,666

22 Claims. (Cl. 230—30)

This invention relates generally to control apparatus for air or gas compressors and more particularly to means for obtaining a close correspondence between the volume of fluid taken from a storage tank for use as an actuating medium and the volume of fluid supplied to the tank by the compressor.

In association with an air compressor the mechanism of the invention operates to control the admission of air to the compression cylinder of the compressor in such a manner as to increase and reduce the volume of air admitted to the cylinder, in response to the fall and rise of the air pressure within the receiver tank. Included in the mechanism of the invention is a novel inlet valve assembly comprising a principal and an auxiliary valve, the latter of which may be closed during a variable portion of the inlet stroke to reduce by a variable amount the volume of air taken into the cylinder for compression. The auxiliary valve may be moved to closed position at any point in the inlet stroke, the time of movement being determined by the air pressure within the receiver. The effect of this method of operation is to maintain the air pressure within the receiver at a substantially constant level without wide fluctuations in power demand on the operating motor of the compressor.

The variable capacity control of this invention represents a departure both in mechanism and mode of operation from the usual regulating apparatus of a compressor. The most common control apparatus of the prior art is one which effects step-by-step unloading of the compressor by permitting the air within the cylinder to be directed into clearance pockets on the compression stroke and be re-expanded into the cylinder on the inlet stroke. These clearance pockets are in close proximity to the cylinder and one disadvantage of this method is that the necessarily small valve area between each pocket and the cylinder causes the air to be moved therethrough at a high velocity with a resulting loss of power. Further, the air being compressed into the pockets at discharge pressure is at a high temperature and there is considerable cooling of the air while in the pockets since conditions are ideal for cooling, that is, the pockets are water jacketed and the air is forced against the cylinder thereof at high velocity. This cooling of the air while in the clearance pockets causes a large portion of the available power to be lost.

Another method of unloading a compressor is to close the intake completely for a few strokes and then open it for a while, the time it remains

open and the time it remains closed depending upon the rapidity with which the receiver pressure changes. This method is objectionable because it causes wide fluctuations in the power demand on the actuating motor since at one instant the compressor is working at full load and the next instant it is working at no load.

Another method sometimes used is to throttle the intake of the compressor in accordance with the demand on the receiver. This method causes considerable heating due to the large number of compressions that take place, and the fact that when the air is throttled there is no appreciable drop in temperature.

Still another method of unloading is that called "free air unloading." In this method the inlet valves at one or both ends of a double acting compression cylinder are held open to allow the air to pass freely through the valves, in and out of the cylinder. This gives either full load or no load for a particular end of the cylinder and causes a disturbance in the electrical system when the compressor is operated by an electric motor. Also, the horse power required to move the air back and forth through the valves represents wasted effort, since the operation serves no useful purpose.

The method of the present invention, in addition to preventing wide fluctuations in power demand, presents other advantages over the methods of the prior art. In limiting the amount of air admitted to the cylinder for compression it permits operation of the compressor with a minimum power consumption, and insures only slight or no disturbance in the electrical system because all cylinders are working under equal loads at all times. Further, when all cylinders are working continuously there is no chance for lubricating oil to collect in the cylinders since any excess will be blown out the discharge valves.

One object of the invention is to decrease power consumption and prevent wide fluctuations in power demand, in a constant speed air compressor, through the provision of control apparatus for varying the capacity of the compressor to equal the demand on the air receiver.

Another object of the invention is to vary the capacity of a compression cylinder by closing the inlet valves during a variable portion of the inlet stroke.

Another object of the invention is to effect closing of the inlet valves under the control of air pressures within the air receiver, in such a manner as to close the valves during a portion of the

inlet stroke, variable in response to variations in receiver pressure.

Another object of the invention is to effect closing of the inlet valves by pressure fluid, forming a part of either a compressed air system or hydraulic system.

Other objects and structural details of the invention will be more apparent from the following description when read in conjunction with the accompanying drawings, wherein:

Fig. 1 is a view, partly in longitudinal section and partly in side elevation, showing the control apparatus, representing one embodiment of the invention, in cooperative relation with a double acting compressor and an air receiver;

Fig. 2 is an enlarged view, in longitudinal section, of a portion of Fig. 1, showing in greater detail the control apparatus of that embodiment of the invention;

Fig. 3 is a view similar to Fig. 1 showing a second embodiment of the invention;

Fig. 4 is an enlarged view, in longitudinal section, of a portion of Fig. 3 showing in greater detail the control apparatus of that embodiment of the invention;

Fig. 5 is a detail view, in longitudinal section, of the control valve and associated operating means of Figs. 3 and 4, showing the operating means disabled and the control valve in closed position;

Fig. 6 is a detail view, taken substantially along the line 6—6 of Fig. 5, showing the adjacent ends of the control valve and its associated operating pawl, in plan; and

Figs. 7 and 8 are diagrams illustrating the pressure fluctuations in the compression cylinder of respective single and double acting compressors, during a typical inlet and compression cycle.

In the two embodiments of the invention illustrated a compressor cylinder 10, of the double acting type and of generally standard construction, is shown in connection with the mechanism of the invention. Referring to Figs. 1 and 3 it will be seen that a piston 11, reciprocable within the cylinder 10, forms, in cooperation with the end walls of the cylinder and an inner side wall 12, a pair of piston chambers C1 and C2. A series of inlet valves 13 and discharge valves 14 are positioned within the cylinder 10 near each end thereof and, by automatic pressure responsive operation, control the flow of air to and from the chambers C1 and C2. In the operation of the compressor, air is drawn from the atmosphere through an inlet 15 and flows past alternate sets of inlet valves 13 to the chambers C1 and C2 where it is compressed by the piston 11 and driven out the discharge valves 14 and through a discharge pipe 16, to a receiver 17 where it is stored for use as an actuating fluid. When moving in a leftward direction, as viewed in Figs. 1 and 3, the piston 11 acts to compress the air previously admitted to chamber C1 and force it past the associated set of discharge valves 14. Leftward movement of the piston expands the size of chamber C2 causing a drop in pressure therein and the automatic opening of the right hand set of inlet valves 13. When moving in a rightward direction this operation is reversed, that is, the air in chamber C2 is compressed and driven therefrom while a fresh supply of air is admitted to the chamber C1. Describing the movement of the piston with reference to the chamber C1, it may be said that when travelling to the right, the piston moves through an inlet

stroke and when travelling to the left moves through a compression stroke.

Only one inlet valve 13 and one discharge valve 14 are shown in the drawings. The construction and operation of each valve in a respective series is the same as the others in the series so that a description of one will suffice for all. Thus the inlet and discharge valves shown are representative of the respective series associated with the piston chamber C1. The description to follow is directed only to a disclosure of the construction and operation of the inlet and discharge valves shown and to a disclosure of the control mechanism associated with one series of inlet valves. 15 The valves 13 and 14 are of the pressure responsive ring type commonly used in this class of machine and are not illustrated in the full details of their construction. The patent to W. H. Callan No. 1,274,383, issued August 6, 1918, may be referred to for a more complete disclosure of this type of valve. Briefly, each valve represents an assembly comprising a perforated valve seat 18, a valve ring 19 and a valve keeper 21 having a projecting portion 20 in threaded engagement with the valve seat. Compression springs 22 (see also Figs. 2 and 4), positioned between the keeper 21 and the ring 19, press the ring against the lower surface of the seat 18 to close the perforations therein. The flow of air past each 25 valve assembly is thus normally prevented and is permitted only when a variation in pressure on opposite sides of the assembly, of sufficient extent to force the ring 19 to open position against the tension of springs 22, occurs. The inlet and 30 discharge valves are, of course, oppositely arranged in the cylinder 10 in order that one will function normally to permit only the admission of air and the other function normally to permit only the discharge of air. 35 40 In regulating the amount of air to be taken into the piston chamber C1, in accordance with the present invention, there is associated with the inlet valve assembly 13 an additional valve ring 23 positioned adjacent the outer surface of the valve seat 18 and movable to an open and closed position with respect to the perforations in the valve seat. The ring 23 may be guided in its movement by any suitable means and is urged outward to ineffective or open position by compression springs 24 positioned in recesses in the 45 valve seat 18. In urging the ring 23 outward the springs 24 press the ring into engagement with the tips of a set of fingers 25 which form a part of the piston assembly 26. At a variable point in each inlet stroke of the piston 11 the piston assembly 26 is forced downward and acts to press the valve ring 23 into engagement with the outer surface of the valve seat 18 to cover the perforations in the seat and thereby cut off the flow of air into the chamber C1 for the remainder of the inlet stroke. The point in the inlet stroke at which the piston assembly 26 moves downward is determined by the pressure of the air within the receiver 17 and varies with variations 50 in the receiver pressure. Thus as the receiver pressure rises the piston assembly 26 operates at an earlier point in the inlet stroke and the volume of air admitted to the piston chamber for compression is reduced to obtain a more even correspondence between supply and demand. Conversely, as the receiver pressure drops, the piston assembly operates at a later point and the volume of air admitted to the cylinder 10 is increased. 55 The piston assembly 26 forms a part of both embodiments of the invention shown, the difference 60 65 70 75 80 85 90 95

between the two embodiments lying in the means for initiating operation of the assembly.

Considering first that form of the invention shown in Figs. 1 and 2 and referring particularly to Fig. 2, it will be seen that the piston assembly 26 comprises, in addition to the fingers 25, an abutment sleeve 27 formed integrally with the fingers 25, a rod 28 passed through the sleeve 27, and a piston head 29 secured to the upper end of the rod 28. The lower end of the rod 28 projects into a recess or guideway 31 formed in the projecting portion 20 of the valve keeper 21, while a compression spring 32 surrounding the rod 28 extends into the abutment sleeve 27 to press the sleeve upward into engagement with a collar 33 formed on the rod 28, and thereby to press the piston assembly as a whole to its upper or ineffective position. The upper end of the rod 28 extends into a chamber 34 through which the piston head 29 reciprocates. The chamber 34 is formed in the upper end of an extension 35 which is preferably cast as an integral part of the valve seat 18. A head piece 36, secured to the upper end of the extension 35, closes the chamber 34 and forms, in cooperation with the extension 35, a space 37 through which communication is established between the chamber 34 and a pressure fluid conducting passage 38 also formed in the extension 35. The passage 38 is connected, by means of a pipe 39, to the receiver tank 17 (Fig. 1), so that air from the receiver is conducted directly to the passage 38 from where it may flow through the space 37 to chamber 34 and act on the upper surface of piston head 29 to force the piston assembly 26 to its lower or effective position. Although the pipe 39 is shown connected to the receiver 17, it will be understood that it may, if desired, be connected to any other suitable source of pressure fluid.

The flow of air through the passage 38 is controlled by a valve 41 movable between a seat 42 in the end of passage 38 that communicates with the space 37, and a seat 43 positioned opposite the passage 38, in the head piece 36. The valve 41 is formed on the lower end of a plunger 44 which passes upward through the head piece 36 and engages the lower surface of a diaphragm 45 secured between the upper end of the piece 36 and a closure plate 46. Through means later to be described, a variable pressure is applied to the upper surface of the diaphragm 45 in opposition to the pressure applied to the lower surface thereof, through the valve plunger 44. When the pressure exerted on the upper surface of the diaphragm 45 is greater than the pressure within passage 38 the valve 41 is held on the seat 42 and prevents the flow of air from the pipe 39 and passage 38 to the chamber 34. When the pressure above diaphragm 45 drops below the pressure within passage 38 valve 41 is forced from the seat 42 to the seat 43, thereby opening passage 38 and permitting the flow of actuating fluid to the piston head 29. Upon the return of valve 41 to seat 42 the space 37 and the portion of chamber 34 above piston head 29 are connected to atmosphere through a set of ports 47, in the piece 36, to which the air flows along the plunger 44.

Pressure above the diaphragm 45 is established by directing compressed air from the piston chamber C1 to a recessed portion 48 of the closure plate 46. As shown in Fig. 2 the left hand end plate of the cylinder 10 is formed with a passage 49 communicating with the chamber C1

and into which air is driven on the compression stroke of the piston 11. From the passage 49 the air is conducted through a pipe 51 into a valve housing 52 where it is forced past a check valve 53 and conducted by a pipe 54 to a chamber 55 formed in the cylindrical end piece 56 of a control element 57. From the chamber 55 the air may pass through another pipe 58 directly to the recessed portion 48 above the diaphragm 45. In the operation of the compressor, air is forced past the check valve 53 to the chamber 55 upon each compression stroke of the piston 11 and acts, through pipe 58, on the upper surface of diaphragm 45 to hold the valve 41 in closed position with respect to the passage 38.

The control element 57 includes, in addition to the cylindrical end piece 56, an intermediate element 59, and a closure plate 61 secured to the upper end of the element 59. The end piece 56 has a threaded engagement with the lower end of the element 59 and is formed with a passage 62 establishing communication between the chamber 55 in end piece 56 and a chamber 63, formed in the lower end of element 59 through the cooperation of end piece 56 and a plug 64 closing the lower end of the element 59 from communication with the upper end. A port 65 connects the chamber 63 to atmosphere and it is through the passage 62, chamber 63 and port 65 that the pressure in chamber 55 and above diaphragm 45 is reduced. The passage 62 is controlled by a valve 66 formed on the lower end of a plunger 67 which extends upward through the intermediate element 59 and engages the lower surface of a diaphragm 68 clamped between the upper end of element 59 and closure plate 61. A compression spring 69, seated on the plug 64 and surrounding the plunger 67 urges the plunger into engagement with the diaphragm 68 to press it upwards, while air conducted by way of a pipe 71 from the receiver 17 (see also Fig. 1) to a recess 72 in the closure plate 61 presses the diaphragm downward. As the receiver pressure above the diaphragm 68 rises and falls the valve 66 is moved away from and towards its seat in passage 62 to increase and reduce the rate of air flow from the chamber 55.

During the compression stroke of the piston 11 the pressure in chamber 55 is increased to a level sufficient to force the valve 41 downward and thereby permit the piston assembly 26 and valve ring 23 to rise to ineffective position. At the end of the compression stroke the supply of air to the chamber 55 stops and, as the air escapes from the chamber along the passage 62, the pressure therein starts to drop, at a definite rate determined by the position of valve 66 with respect to passage 62. The pressure continues to drop during the inlet stroke and, at some point during the stroke, will become insufficient to hold the valve 41 down, whereupon this valve will be forced off its seat 42 and the piston assembly 26 actuated in the manner previously described to close the inlet valve for the remainder of the inlet stroke. It will be evident that the point in each inlet stroke at which the piston assembly 26 is operated is determined by the size of the vent opening between the valve 66 and passage 62 and that the position of the valve 66 with respect to the passage 62 is determined by the pressure within the receiver 17. Thus, as the receiver pressure rises the pressure in chamber 55 is vented more quickly and the inlet valve closed earlier in the inlet stroke. As the receiver pressure drops, a correspondingly longer time is re-

quired to vent the chamber 55 and the inlet valve remains open for a longer portion of the inlet stroke.

Exhaust port 65, instead of being connected to atmosphere, may be arranged to communicate continuously with the cylinder space as by a pipe 65a (Fig. 2) connected to pipe 51.

In the compressor as actually constructed, each inlet valve in the cylinder 10 has an auxiliary valve ring 23 associated therewith and each may have also an individual piston assembly 26. A simplified form of this principle may be used, however, requiring only one piston assembly 26 in each end of the cylinder. In this construction, the rings 23 of the remainder of the inlet valves are so balanced that they will close automatically due to the increased air velocity caused by the closing of the positively controlled valve, which thus serves as a pilot valve. It should also be understood that although the auxiliary valve ring 23 is said to be moved into engagement with the valve seat 18 by the piston assembly 26, it is only necessary that the ring be positively actuated during a portion of its movement to closed position. As the valve ring approaches the seat 18 the flow of air into the piston chamber is restricted and the consequent increase in the velocity of the flow pulls the ring into position against the valve seat. One control element 57 and associated control apparatus is required for each end of the cylinder in a double acting compressor.

In Figs. 7 and 8 the pressure fluctuations within the piston chamber, caused by the closing of the inlet valve during a typical inlet stroke, are indicated diagrammatically. Fig. 7 illustrates the pressure changes in a single acting compressor, and Fig. 8 the changes in a double acting compressor. In these curves, the ordinates represent pressure and the abscissae indicate volume.

Referring to Fig. 7, the vertical broken lines A and B may be considered to represent the opposite limits of movement of the piston 11, and the horizontal broken lines C and D the normal pressure limits within the piston chamber; the line C representing the discharge pressure and the line D the intake pressure which may be atmospheric. The solid line depicts the expansion and compression of the air as the piston moves through a typical inlet and compression cycle. Following the solid line and starting at point E it will be seen that as the piston moves to the right on the inlet stroke the slight amount of air not discharged from the piston chamber expands rapidly and shortly after the start of the inlet stroke reaches a pressure slightly lower than the normal intake pressure. At this point, indicated as F in the drawing, the inlet valve ring 19 is forced off its seat and air begins to flow into the piston chamber. As the piston 11 continues through the inlet stroke, the inlet valve remains open and the pressure within the piston chamber is established at the normal intake level and the volume of air within the chamber increases. While this operation is taking place, however, the pressure in chamber 55, in control element 57, is dropping by reason of vent opening 62 and, within a period of time determined by the size of the vent opening, becomes insufficient to hold control valve 41 closed. At this point, indicated as G in the drawings, air passes from the receiver 17, or other pressure source, to the chamber 34 to actuate the piston assembly 26 and thereby move the auxiliary valve ring 23

to closed position. The flow of air to the piston chamber is thus cut off at point G of the inlet stroke so that the remainder of this stroke is performed without effect so far as increasing the volume of air within the piston chamber is concerned. During this remaining portion of the inlet stroke the increasing size of the piston chamber allows the air already admitted thereto to expand, causing the pressure within the chamber to drop below the normal intake pressure.

As the piston 11 returns leftward on the compression stroke the piston chamber is gradually reduced in size and the pressure of the air therein rises until, at a point H near the end of the compression stroke, it goes slightly above the normal discharge pressure and forces open the discharge valve 14. During the remainder of the compression stroke, the air is discharged from the piston chamber and directed to the receiver 11. During the compression stroke a portion of the air in the piston chamber is also directed, by way of passage 49 and pipe lines 51 and 54, to the pressure chamber 55 and, at some point in this stroke (variable in accordance with the volume of air admitted to the piston chamber), the pressure in chamber 55 will reach a height sufficient to return valve 41 to closed position and thereby cut off the supply of actuating fluid to the piston assembly 26. When this occurs the piston assembly is immediately returned to its upper ineffective position by the spring 32, and the valve ring 23 is moved to open position by the springs 24. The pressure in chamber 55 begins to drop again at the end of the compression stroke.

In Fig. 8 the typical operation chosen for illustration is one in which the pressure fluctuations in each chamber of the compression cylinder are identical. As long as the demand upon the air receiver remains constant the pressure fluctuations within the compression cylinder are the same throughout successive cycles of operation. Each change in the demand on the receiver, however, is reflected in a corresponding change in the volume of air admitted to the cylinder for compression.

The second of the illustrated embodiments of the invention, shown in Figs. 3 and 4, presents a means for actuating the piston assembly 26 by hydraulic pressure. Referring particularly to Fig. 4 it will be seen that in this instance the extension 35A of the valve seat 18 is of a more simple construction, having only a chamber 34 closed by a closure plate 73. A suitable liquid, such as oil, is pumped into the upper end of the chamber 34, through a pipe 74, and presses upon the piston head 29 to force the piston assembly 26 downward and thereby close the inlet valve. The pipe 74 extends outside the cylinder 10 and connects, at its outer end, to a tubular extension 75 of a control element 76. The outer end of the pipe 74 opens into a chamber 77, in extension 75, to which oil is supplied from a reservoir 78 (Fig. 3) by means of an oil pump 79 and connecting pipe 81. The pump 79, and its associated pressure relief valve 82, are given a merely diagrammatic representation here, since their construction and operation may follow any conventional practice. The pump is operated by a constantly rotating shaft 83 which may be connected directly to the main crankshaft 84, of the compressor, or positively driven in any other suitable manner. Thus, as the shaft 83 rotates, oil is pumped from the reservoir 78 through the pipe 81 to the chamber 77 from where it may

flow into the pipe 74 and also through a port 85 (Fig. 4) by which communication is established between the chamber 77 and a chamber 86 also formed in the extension 75. The chamber 86 communicates, through a pipe 81, with the reservoir 18 so that oil flowing into this chamber is returned directly to the reservoir. A plunger valve 88 is movable within the extension 75 to an open and closed position with respect to the port 85 to control the flow of oil to the chamber 86. With the valve 88 in open position no resistance is offered to the circulation of the oil, which then flows continuously from the reservoir by way of pipe 81 and back to the reservoir by way of pipe 81. The oil flows also into the pipe 74, at this time, but due to its lack of pressure is unable to force the piston assembly 26 downward against the tension of the spring 32. With the valve 88 in closed position the free circulation of the oil back to the reservoir is interrupted and, as the pump 79 continues to force oil into the chamber 77, the pressure within pipe 74 and above the piston head 29 increases to a point sufficient to actuate the piston assembly 26 and close the inlet valve.

Thus, in this embodiment of the invention, the opening and closing of the inlet valve is controlled by the plunger valve 88 which acts, in a manner to be described, to restrict the circulation of the oil through the hydraulic system at a variable point in each inlet stroke. As shown in Figs. 4 and 5 the valve 88 passes through the chamber 77, port 85 and chamber 86 and is formed with a reduced portion 89, adjacent these openings, about which the oil is free to pass from chamber 77 to chamber 86. In the closed position of the valve 88, shown in Fig. 5, the reduced portion 89 thereof is shifted out of the chamber 77 and a portion of larger diameter enters the port 85 and cuts off the flow of oil to the chamber 86. In the open position of the valve, shown in Fig. 4, the reduced portion 89 extends into the chamber 77 and the return of the oil through port 85 and chamber 86 is unrestricted. The left hand end of the valve 88 (as viewed in Fig. 4) extends beyond the outer end of the extension 75 and is formed with a head 91 which limits movement of the valve in a rightward direction. A housing 92, secured to the outer end of the extension 75, encloses the head 91 and supports a compression spring 93 which urges the head into engagement with the end extension 75 to place the valve 88 in the closed position of Fig. 5. The right hand end of the plunger valve 88 extends beyond the inner end of the extension 75 and is formed with a shoulder 94 adapted to be engaged by a pawl 95 mounted upon an eccentric disc 96 (Fig. 3) secured to the shaft 83. As the shaft 83 and eccentric 96 rotate, the pawl 95 reciprocates and, by reason of its engagement with the shoulder 94, imparts, in cooperation with the spring 93, a similar motion to the valve 88. The pawl 95 is urged downward, into engagement with the valve 88, by a light spring 90, and moves in a certain timed relation to the movement of the piston 11. Slightly before the end of the compression or discharge stroke the pawl engages the shoulder 94 and moves the valve 88 forward, against the tension of spring 93, to open position. The valve 88 continues to move forward during the inlet stroke but at some point during this stroke the pawl 95 is disengaged from the shoulder 94 whereupon the valve snaps back to closed position and the operation of closing the inlet valve is initiated. The means for disabling the

pawl 95 resides in a cam plate 97 formed with a pair of upstanding arms 98, having inclined surfaces 99 (see also Fig. 6), between which the reduced right hand end of the valve 88 moves. The cam plate 97 is secured to the upper end of a rod 101 movable within the control element 76 to place the inclined surfaces 99 to a plurality of positions with respect to the pawl 95. Thus at some point during the forward movement of the pawl 95, the nose thereof engages the inclined surfaces 99 and, as the pawl continues to move forward, is cammed out of engagement with the shoulder 94, whereupon the valve 88 is returned immediately to closed position by the spring 93. The variable positioning of the cam plate 97 is accomplished against the tension of a spring 102, which urges the rod 101 downward, and is brought about through the application of receiver pressure against the lower surface of a diaphragm 103, the upper surface of which is engaged by the lower end of rod 101. The diaphragm 103 is clamped between the lower end of control element 76 and a closure plate 104, and air from the receiver 17 is conducted to a recess 105 in the plate 104, by means of a connecting pipe 106. The rise and fall of the pressure in receiver 17 is thus reflected in a corresponding movement of the diaphragm 103 and of the cam plate 97 to advance or delay the point in the inlet stroke at which the pawl 95 is disabled.

In reading the diagrams of Figs. 7 and 8 in connection with the second embodiment of the invention, point G indicates the point in the inlet stroke, of the examples shown, at which the auxiliary inlet valve 23 closes in response to the release of valve 88.

What is claimed is:

1. A valve assembly comprising a ring valve arranged to prevent the passage of air through the assembly, a second ring valve arranged to prevent the passage of air through the assembly, a yielding means urging the first said valve to effective position, a yielding means urging the second said valve to ineffective position, and means for moving the second said valve toward effective position.

2. A valve assembly comprising a ring valve arranged to prevent the passage of air through the assembly, a second ring valve arranged to prevent the passage of air through the assembly, a yielding means urging the first said valve to effective position, a yielding means urging the second said valve to ineffective position, and pressure responsive means for moving the second said valve toward effective position, said means including a piston assembly having a plurality of contact fingers engaging the second said valve.

3. A valve assembly comprising a perforated valve seat, a first valve positioned adjacent said valve seat on one side thereof and movable to an open and closed position with respect to the perforations therein, a second valve positioned adjacent said valve seat on the opposite side thereof and movable to an open and closed position with respect to the perforations therein, a yielding means urging said first valve to closed position, a yielding means urging said second valve to open position, and means cooperative with said second valve and movable relatively to said valve seat for moving said second valve toward closed position.

4. A valve assembly comprising a perforated valve seat, a first valve positioned adjacent said valve seat on one side thereof and movable to an open and closed position with respect to the

perforations therein, a second valve positioned adjacent said valve seat on the opposite side thereof and movable to an open and closed position with respect to the perforations therein, a yielding means urging said first valve to closed position, a yielding means urging said second valve to open position, a valve seat extension secured to said valve seat, a piston chamber formed in said valve seat extension, and a piston assembly supported within said valve seat extension for moving said second valve toward closed position, said piston assembly comprising a piston head movable within said piston chamber and a set of contact fingers engaging said second valve.

5. In a compressor, the combination of a piston chamber, an inlet valve and a discharge valve controlling the flow of air to and from said chamber, a piston movable within said chamber through an inlet stroke and a compression stroke, during the former of which air is admitted to said chamber through said inlet valve and during the latter of which the air so admitted to the chamber is compressed and discharged through said discharge valve, a receiver to which the air discharged from said chamber is directed and stored for use as an actuating fluid, and means for closing said inlet valve during a variable portion of the inlet stroke to vary the volume of air admitted to said chamber in accordance with the varying demand on said receiver.

6. In a compressor, the combination of a piston chamber, an inlet valve and a discharge valve controlling the flow of air to and from said chamber, a piston movable within said chamber through an inlet stroke and a compression stroke, during the former of which air is admitted to said chamber through said inlet valve and during the latter of which the air so admitted to the chamber is compressed and discharged through said discharge valve, a receiver to which the air discharged from said chamber is directed and stored for use as an actuating fluid, normally ineffective means for closing said inlet valve to prevent the flow of air into said chamber, and means controlled by the air pressure within said receiver for rendering said closing means effective during a portion of the inlet stroke variable in accordance with the degree of pressure within said receiver.

7. In a compressor, the combination of a piston chamber, an inlet valve assembly controlling the admission of air into said piston chamber, an auxiliary valve comprised in said inlet valve assembly for preventing the passage of air into said piston chamber, pressure responsive means for moving said auxiliary valve to closed position, a pressure fluid system including means for directing pressure fluid to said pressure responsive means, and settable means controlling the circulation of pressure fluid in said system to render said pressure fluid effective and ineffective to actuate said pressure responsive closing means.

8. In a compressor, the combination of a piston chamber, a receiver to which air is directed from said piston chamber, an inlet valve assembly controlling the admission of air into said piston chamber, an auxiliary valve comprised in said inlet valve assembly for preventing the passage of air into said piston chamber, pressure responsive means for moving said auxiliary valve to closed position, a pressure fluid system including means for directing pressure fluid to said pressure responsive means, settable means con-

trolling the circulation of pressure fluid in said system to render said pressure fluid effective and ineffective to actuate said pressure responsive closing means, means for setting said settable means in position to render the pressure fluid in said system ineffective to operate said pressure responsive closing means, and means controlled by the pressure of the air in said air receiver for disabling said last mentioned means.

9. In a compressor, the combination of a piston chamber, a receiver to which air compressed within said piston chamber is directed, an inlet valve assembly controlling the admission of air into said piston chamber, an auxiliary valve comprised in said inlet valve assembly for preventing the passage of air past said assembly, a yielding means urging said auxiliary valve to ineffective position, and means controlled by the air pressure within said receiver for moving said auxiliary valve to effective position.

10. In a compressor, the combination of a piston chamber, an inlet valve assembly controlling the admission of air into said piston chamber, an auxiliary valve comprised in said valve assembly and movable from an open to a closed position to prevent the passage of air through said assembly, a yielding means urging said auxiliary valve to open position, pressure responsive means for moving said auxiliary valve to closed position, said pressure responsive means comprising a piston assembly having a set of contact fingers engaging said auxiliary valve, means for directing pressure fluid to said piston assembly to actuate said assembly, and means for controlling the flow of pressure fluid to said piston assembly to cut off and establish such flow alternatively.

11. In a compressor, the combination of a piston chamber, an air receiver to which air compressed within said piston chamber is directed, an inlet valve controlling the admission of air into said piston chamber, pressure responsive means for closing said inlet valve to prevent the flow of air into said piston chamber, a passage conducting air from said receiver to actuate said pressure responsive means, a pressure chamber to which air is directed from said piston chamber, a control valve movable in response to pressure variations between said passage and said pressure chamber to open and closed positions with respect to said passage, and means movable in response to pressure variations in said air receiver for reducing the pressure of the air in said pressure chamber at a variable rate.

12. In a compressor, the combination of a piston chamber, an air receiver to which compressed air is directed from said piston chamber, an inlet valve controlling the admission of air into said piston chamber, pressure responsive means for closing said inlet valve to prevent the flow of air into said piston chamber, a passage conducting air from said receiver to actuate said pressure responsive means, a pressure chamber to which air is directed from said piston chamber, a control valve movable in response to pressure variations between said passage and said pressure chamber to open and closed positions with respect to said passage, a vent opening said pressure chamber to atmosphere, and means movable in response to pressure variations in said receiver for varying the size of said vent to increase or reduce the rate of reduction of pressure in said pressure chamber.

13. In a compressor, the combination of a piston chamber, a piston movable within said chamber through an inlet stroke and a compression

stroke, during the former of which air is admitted to said chamber and during the latter of which the air so admitted to the chamber is compressed and discharged therefrom, a receiver to which the air discharged from said chamber is directed and stored for use as an actuating fluid, an inlet valve controlling the admission of air into said piston chamber, pressure responsive means for closing said inlet valve to prevent the flow of air into said chamber, a passage conducting air from said receiver to actuate said pressure responsive means, a control valve movable to a closed position against the pressure of the air in said receiver to close said passage, a pressure chamber to which air is directed from said piston chamber on the compression stroke, means for applying the pressure within said pressure chamber upon said control valve to urge said control valve to closed position, a vent connecting said pressure chamber to atmosphere whereby the pressure acting on said control valve is reduced during the inlet stroke to allow said control valve to be moved to open position, and means movable in response to pressure variations in said receiver for varying the size of said vent to increase or reduce the rate of reduction of pressure in said pressure chamber and thereby advance or delay the point in the inlet stroke at which said control valve is moved to open position and said inlet valve closed.

14. In a compressor, the combination of a piston chamber, an inlet valve controlling the admission of air into said chamber, pressure responsive means for closing said inlet valve to prevent the flow of air into said chamber, a hydraulic system including means for applying hydraulic pressure to said pressure responsive means to actuate said means, a yielding means resisting actuation of said pressure responsive means and preventing actuation of said means by the normal pressure in said hydraulic system, means reciprocable from and to a position restricting the free circulation of fluid in said system to increase the pressure therein above its normal level, operating means for effecting reciprocation of said reciprocable means, and means for controlling the operation of said reciprocable means to effect its movement to restricting position during a variable portion of the operation of said operating means.

15. In a compressor, the combination of a piston chamber, a piston movable within said chamber through an inlet stroke and a discharge stroke during the former of which air is admitted to said chamber and during the latter of which the air so admitted is compressed and discharged therefrom, an inlet valve controlling the admission of air into said chamber, pressure responsive means for closing said inlet valve to prevent the flow of air thereby, a hydraulic system including means for applying hydraulic pressure to said pressure responsive means to actuate said means, a yielding means resisting actuation of said pressure responsive means and preventing actuation of said means by the normal pressure in said hydraulic system, means reciprocable from and to a position restricting the free circulation of fluid in said system to increase the pressure therein above its normal level, and means for effecting operation of said reciprocable means in a timed relation to the movement of said piston.

16. In a compressor, the combination of a piston chamber, an inlet valve controlling the admission of air into said chamber, pressure

responsive means for closing said inlet valve to prevent the flow of air into said chamber, a hydraulic system including means for applying hydraulic pressure to said pressure responsive means to actuate said means, a yielding means resisting actuation of said pressure responsive means and preventing actuation of said means by the normal pressure in said hydraulic system, means reciprocable from and to a position restricting the free circulation of fluid in said system to increase the pressure therein above its normal level, a yielding means urging said reciprocable means to restricting position, operating means for effecting reciprocation of said reciprocable means whereby said reciprocable means reaches restricting position at a constant point in the operation of said operating means, and means settable to a plurality of positions relative to said operating means for disabling said operating means at a variable point in the operation thereof.

17. In a compressor, the combination of a piston chamber, a piston movable within said chamber through an inlet stroke and a compression stroke during the former of which air is admitted to said chamber and during the latter of which the air so admitted to the chamber is compressed and discharged therefrom, a receiver to which the air discharged from said chamber

is directed and stored for use as an actuating fluid, an inlet valve controlling the admission of air into said piston chamber, pressure responsive means for closing said inlet valve to prevent the flow of air into said chamber, a hydraulic system including means for applying hydraulic pressure to said pressure responsive means to actuate said means, a yielding means resisting actuation of said pressure responsive means and preventing actuation of said means by the normal pressure in said hydraulic system, means reciprocable from and to a position restricting the free circulation of fluid in said system to increase the pressure therein above its normal level, a yielding means urging said reciprocable means to restricting position, operating means movable in a timed relation to the movement of said piston to move said reciprocable means from restricting position during the inlet stroke, means for disabling said operating means during its movement in the inlet stroke, whereupon said reciprocable means is returned to restricting position for the remainder of the inlet stroke, and means movable in response to pressure variations in said air receiver for setting said disabling means to a plurality of disabling positions relative to said operating means to advance or delay the point in the inlet stroke at which said operating means is disabled.

18. In a compressor or like machine having a positively driven air compressing piston, the combination of a valve assembly controlling the intake of air into said compressor and comprising a control valve, an auxiliary valve controlling the passage of air through the assembly, a yielding means holding said auxiliary valve normally ineffective or in open position, actuating means for moving said auxiliary valve toward effective or closed position, and means operating in a timed relation to the movement of said compressor piston for successively enabling and disabling said actuating means.

19. A compressor or like machine according to claim 18 having a receiver for the storage of compressed air, and characterized by means controlled by the air pressures within said receiver

for varying the timed relation in the operations of said enabling and disabling means and said compressor piston.

20. In a compressor or like machine having a positively driven air compressing piston, the combination of a valve assembly controlling the intake of air into said compressor and comprising a control valve, an auxiliary valve controlling the passage of air through the assembly, a yielding means holding said auxiliary valve normally ineffective or in open position, actuating means for moving said auxiliary valve toward effective or closed position, means for enabling and disabling said actuating means, means for initiating operation of said enabling and disabling means in a timed relation to the operation of said air compressing piston, and settable means controlling the operation of said last named means to vary the timed relation in the operations of said enabling and disabling means and of said piston.

21. In a compressor or like machine having a positively driven air compressing piston movable through successive inlet and compression strokes, during the former of which air is admitted to the compressor and during the latter of which the air so admitted is compressed and discharged from the compressor, the combination of a receiver to which the air discharged from said

compressor is directed and stored for use as an actuating fluid, means settable to effective and ineffective positions for restricting the admission of air to said compressor, means for moving said settable means to effective position during a variable portion of each inlet stroke of said air compressing piston, and means responsive to pressure variations in said air receiver for controlling the operation of said last named means.

22. Control apparatus for a compressor having an air compressing piston movable through successive inlet and discharge strokes, comprising normally inactive means for restricting the admission of air to the compressor, means operating in a timed relation to the movement of said piston for initiating operation of said restricting means, said means acting to hold said restricting means in active operation during a part of each of a series of inlet strokes of the piston to permit the free entry of air into the compressor only during the remaining portion of an inlet stroke, and means for varying the timed relation to the operations of said initiating means and said piston to lengthen and shorten the period of free air entry in each of the series of inlet strokes.
